UNITED STATES PATENT OFFICE.

ORMUS D. HAMMOND, OF WYOMING, NEW YORK.

TOWEL-HOLDER.

965,707.

Specification of Letters Patent. Patented July 26, 1910.

Application filed November 23, 1909. Serial No. 529,538.

To all whom it may concern:

Be it known that I, ORMUS D. HAMMOND, a citizen of the United States, and a resident of Wyoming, in the county of Wyoming and State of New York, have invented 5 certain new and useful Improvements in Towel-Holders, of which the following is a specification.

This invention is an improvement in 10 towel holders or holders designed for towels or other cloths and the invention consists in certain novel constructions and combinations of parts as will be hereinafter described and claimed.

15 In the drawing Figure 1 is a perspective view of the invention as in use. Fig. 2 is a side view thereof with the holder in contracted position and Fig. 3 is a side elevation with the holder expanded as when a 20 towel or other cloth is held within the gripping portion.

As shown the holder A is bent from spring wire and is formed with the lower contracted portion A' between which the towel 25 or other cloth is gripped as shown in Fig. 1, and the arms A² of the holder extending upwardly from the contracted portion A' are provided at their free ends with inwardly projecting branches A³ from which 30 the loops A⁴ are bent, the said loops being disposed reversely as shown in the drawings and being of sufficient width to permit the play of the loops in the supporting eye B when the parts are applied for use, as will 35 be understood from Figs. 2 and 3 of the drawing. It will be noticed that the eye B is disposed horizontally so that the edge of the holder may hang against the wall thus supporting the holder edgewise with respect 40 to the wall and thereby facilitating the insertion and removal of the cloth in the use of the invention. By the reverse arrangement of the loops A⁴, the arms A² can be spread as desired, the eye limiting the 45 spreading movement in such manner as to prevent any breakage of the holder at the lower end a' of the contracted cloth gripping portion A'.

It will be noticed that the reversely disposed loops A⁴ rest flatwise side by side and in close proximity and slide upon each other in opening and closing movements of the

arms A² and also that the weight of the cloth and holder in the use of the invention operates to draw the arms toward each other 55 by the action of the loops upon their supporting device. The loops rest flatwise side by side and approximately in the plane of the body of the holder and they slide upon each other in the plane of the body of the 60 holder in the opening and closing movement of the holder as will be understood from the drawings. This construction is an important feature of my invention as well as the particular construction by which the loops 65 are formed and supported on the inwardly extending arms A³ which project in reverse directions and support their respective loops as shown.

The holders may be made of any suitable 70 metallic wire and can be nickel-plated or otherwise finished or coated as may be desired by the manufacturer or purchasers.

I claim:

1. A holder for towels and other cloths 75 consisting of wire bent to form a contracted portion mid-way between its ends and having arms extending upwardly from said contracted portion and provided at their upper ends with inwardly extending portions 80 and with loops bent therefrom and resting side by side and in close proximity, the said loops being reversely disposed and resting side by side, and a supporting device consisting of an eye receiving said loops and 85 disposed horizontally, all substantially as and for the purposes set forth.

2. A holder for towels and similar cloths having a contracted gripping portion, arms 90 extending upwardly therefrom and provided at their upper ends with inwardly extending portions projecting in reverse directions and having at their ends loops arranged approximately in the plane of the body of the holder and resting side by side and movable 95 upon each other in the plane of the holder in the opening and closing movements of the device, all substantially as and for the purposes set forth.

ORMUS D. HAMMOND.
